[57] CLAIM

The ornamental design for a broadband antenna, as shown and described.

DESCRIPTION

FIG. 1 is a perspective view taken from the front of a broadband antenna showing my new design;

FIG. 2 is a perspective view taken from the rear of the broadband antenna of FIG. 1;

FIG. 3 is a front elevational view thereof;

FIG. 4 is a top plan view thereof;

FIG. 5 is a rear elevational view thereof;

FIG. 6 is a right side elevational view, the left side being a mirror image thereof;

FIG. 7 is a bottom plan view thereof;

FIG. 8 is a right side elevational view thereof, with the antenna tilted 30° from the vertical position of FIG. 6; and,

FIG. 9 is a top plan view thereof, with the antenna rotated 45° from the horizontal position of FIG. 4.

The broken line showing of the dipoles is for illustrative purposes only and forms no part of the claimed design.

FIG. 2

FIG. 1

FIG. 3

FIG. 4

FIG. 5

FIG. 6

FIG. 7

FIG. 8

FIG. 9
